UNITED STATES PATENT OFFICE.

ARTHUR LEE LIGON, OF PECOS, TEXAS.

WELL-CYLINDER.

1,073,257.

Specification of Letters Patent. Patented Sept. 16, 1913.

Application filed June 4, 1912. Serial No. 701,588.

To all whom it may concern:

Be it known that I, ARTHUR L. LIGON, a citizen of the United States, residing at Pecos, in the county of Reeves and State of 5 Texas, have invented certain new and useful Improvements in Well-Cylinders, of which the following is a specification, reference being had therein to the accompanying drawing.

- 10 This invention relates to pumps and has special reference to a pump having a reciprocating piston and being adapted for use in a deep well, where the pump cylinder is difficult of access.
- 15 The principal object of the invention is to improve and simplify the general construction of devices of this character.

A second object of the invention is to provide a form of pump wherein all of 20 the working parts including the barrel can be removed without difficulty and without the use of special tools.

With the above and other objects in view, this invention consists in general of certain 25 novel constructions, combinations and arrangements of parts, as will be hereinafter fully described, illustrated in the accompanying drawings, and specifically claimed.

In the accompanying drawings, like characters of reference indicate like parts in the several views, and Figure 1 is a vertical section through a pump constructed in accordance with this invention. Fig. 2 is a side elevation thereof. Fig. 3 is a section of the 35 outer casing of such a pump. Fig. 4 is a section through the casing and working barrel with the piston and attached parts shown in elevation. Fig. 5 is an enlarged detail section through the piston. Fig. 6 is an enlarged detail section of a certain packing 40 device and valve arrangement used in connection herewith. Fig. 7 is a section on the line 7—7, Fig. 1. Fig. 8 is a section on the line 8—8, Fig. 6.

45 In the present embodiment of the invention there is disclosed a well tube 10 of the ordinary sectional type and at the lower end of this tube there is provided an inverted frusto-conical pipe-fitting 11 which is 50 screwed on the tube and which is provided interiorly with a series of ribs 12 extending around the same adjacent the bottom. To the lower end of this fitting 11 is attached a section of tubing 13, preferably of the same size as the tubing 10 and on the lower end 55 of this member 13 is a second inverted frusto-

conical fitting 14 but it is to be noted that this second fitting 14 has its major diameter substantially the same as the minor diameter of the fitting 11. Below the fitting 14 60 may be provided, if desired, a tube 15, although if the fitting 14 itself is immersed in the water this tube is unnecessary. Seated in the fitting 14 is a packing valve device which comprises a cylindrical body portion 65 16 having a reduced end 17 below the body, this end being threaded exteriorly as at 18 at its lower extremity. Above the body 16 there is provided a flange 19 and in spaced relation to this flange 19 is a cup-shaped 70 head 20 wherein is screwed the barrel 21 of the pump. Within the cup-shaped head 20 is a threaded boss 22 whereon is screwed a valve cage 23 having open sides and being provided with a centrally disposed guide 75 opening 24 in its bridge 25. Through the body from end to end extends a passage 26. Mounted upon the reduced portion 17 of the body is a ring 27 having a frusto-conical lower end 28 and being provided with a series of port openings 19. Screwed upon the threaded portion of the end 17 is a second 80 ring 30 of inverted frusto-conical form and having the same degree of taper as the interior at the fitting 14. This ring is also 85 provided with a series of port openings as indicated at 31 and its smaller end is equipped with a plurality of lugs 32 to enable the same to be tightened up with a suitable tool. Surrounding the reduced frusto- 90 conical lower part of the ring 27 is a cup packing 33, of leather or the like, and the edges of this packing extend between the two rings 27 and 30 and are clamped in position by the ring 30. Surrounding the body 16 95 is an annular valve disk 34 on the lower face of which is provided a suitable packing 35 such as leather or the like, and this packing is held in position by means of an annular washer 36 held on the valve disk by a screw 37. It is to be noted that the maximum diameter of the entire device as thus assembled is less than the minimum diameter 100 interiorly of the pipe-fitting 11.

Above the boss 22 there is mounted in the 105 cage 23 a valve 38, having on its surface a packing 39 of leather or the like, and this packing is held in position by means of a washer 40 and screw 41. The upper end of the barrel 21 is screwed into the ring 42. 110 This ring forms the lower portion of a frusto-conical member 43 provided with lat-

eral ports 44 wherein are pivoted dogs 45. These dogs are provided with teeth 46 which engage the ribs 12 of the frusto-conical member 11. The member 43 has a downwardly-projecting boss 47 located centrally thereof and in this boss is screwed the reduced lower end 48 of a tubular member having a body 49 and a flange 50 above said body. On this tubular member between the body and the ring 43 is a second ring 51 having a reduced frusto-conical end 52 which is surrounded by suitable packing 53 of leather or the like, and the packing has its lower edge clamped between the rings 43 and 51.

Through the rings 43 and 51 extend ports 54 for the passage of water, and on the body 49 there is provided a valve 55 similar in all respects to the valve disk 34. Springs 56 are carried in the lateral ports and serve to normally urge the toothed ends of the dogs outwardly.

At 57 is a coupling which is arranged to be attached to a center rod, the lower end whereof is indicated at 58. Screwed into the bottom of the coupling 57 is a valve cage 59 to the lower end whereof is fixed a tube 60 which extends through a packing gland 61 carried on the upper end of the member 48 above the flange 50.

Upon the lower end of the tube 60 there is provided a hollow piston 61 and immediately above this piston 61 is a dog-operating cam 62. On this hollow piston 61 there is provided a series of metallic rings 62 between which are fitted leather packing rings 63. It is to be noted that these rings are cup rings and are turned in opposite directions so that no matter which way the piston moves the water will be prevented from escaping past the piston.

In the cage 59 is a valve 64, precisely similar in construction to the valve 38, and each of these valves is provided with a stem 65 movable in a suitable guide.

In the ordinary operation of the pump as the piston descends, the valve 64 will open and allow any water that may be in the barrel to flow up through the tube 60 into the tube 10 above the valve 55. At the same time this downward movement will close the valve 55 and open the valve 34 permitting water to flow into the water space between the tube 13 and the barrel 21. When the piston moves upward the valve 64 will close and the valve 38 will open, permitting water to flow up into the barrel 21. At the same time this upward movement of the piston will close the valve 34 and open the valve 55 so that any water held above the piston will be forced out through the ports 54.

This operation is repeated and the water is continually pumped on both strokes of the piston as will be apparent from the foregoing.

Whenever it is desired to take the device

apart for repairs, it is merely necessary to lift the sucker rods until the cam member 62 contacts with the lower ends of the dogs. This will cause the upper ends to move inward as disclosed in Fig. 1 and, in consequence, will free the barrel from the tubing. Further upward movement of the sucker rod will result in the barrel and both the frusto-conical packing devices being raised and they may be lifted entirely clear of the tubing 10 until access may be had thereto for the purpose of repairing or repacking, as may be desired.

There has thus been provided a simple and efficient device of the kind described, and for the purpose specified.

It is obvious that many minor changes may be made in the form and construction of the device without departing from the material principles thereof and it is therefore not wished to confine the invention to the exact form herein shown and described, but it is wished to include all such as properly come within the scope of the appended claims.

Having thus described the invention, what is claimed as new, is:

1. In a pump of the class described, a casing including a pair of seats, plugs fitting said seats, a barrel carried by said plugs, a hollow reciprocable piston mounted in said barrel, dogs carried by one of said plugs, ribs on said casing releasably engaged by said dogs, and means to release said dogs, said means including a hollow piston rod connected to said piston, a cam block on said rod to engage said dogs, each of said plugs being provided with a centrally disposed passage and a series of annularly disposed ports surrounding said passages, said rod passing through the passage of one of said plugs and carrying a valve cage above said plug, a valve cage on the lower plug, valves in said cages, and ring valves covering said ports.

2. In a pump of the class described, a casing including plug seats in spaced relation, plugs fitting said seats, said plugs being of graduated size and all but one arranged to pass through the first seat, a pump barrel carried by said plugs, a hollow piston reciprocably mounted in said barrel, dogs carried by one of said plugs, ribs on said casing releasably engaged by said dogs, and means to release said dogs, said means including a hollow piston rod connected to said piston, a cam block on said rod to engage said dogs, each of said plugs being provided with a centrally disposed passage and a series of annularly disposed ports surrounding said passages, said rod passing through one of said passages and carrying a valve cage above the upper plug, a valve cage on the lower plug, valves in said cages, and ring valves covering said ports.

3. In a pump of the class described, a casting including plug seats in spaced relation, plugs fitting said seats, said plugs being of graduated size and each being of dimensions 5 to permit its passage outward from said seats through the remainder of the seats, a barrel carried by said plugs, a hollow piston reciprocably mounted in said barrel, dogs carried by one of said plugs, ribs on said 10 casing releasably engaged by said dogs, and means to release said dogs, said means including a hollow piston rod connected to said piston, a cam block on said rod to engage said dogs, each of said plugs being 15 provided with a centrally disposed passage and a series of annularly disposed ports surrounding said passages, said rod passing through one of said passages and carrying a valve cage above the upper plug, a valve 20 cage on the lower plug, valves in said cages, and ring valves covering said ports.

4. In a pump of the class described, a casting including a pair of seats, plugs fitting in said seats, a barrel carried by said plugs, 25 the lower plug comprising a tubular body portion having a head at its upper end with which said barrel is connected, a flange formed adjacent said head, the lower end of said body portion being reduced to form 30 an abutment intermediate the length of said body portion, conical rings mounted upon the lower end portion of said body portion and provided with alined openings, a valve disk mounted upon said body portion above 35 said conical rings for closing the openings formed therein, said flange limiting the upward movement of said valve disk, a valve housing carried by said body portion within said barrel, a valve in said housing, a piston 40 ton mounted in said valve, and a piston rod entering said valve for operating said piston.

5. In a pump of the class described, a casting including a pair of seats, plugs fitting in said seats, a barrel carried by said plugs, 45 the upper plug comprising a tubular body portion, a flange adjacent the upper end of said body portion, a conical ring rigidly

mounted upon the lower end portion of said body portion and provided with lateral ports terminating in openings passing through the 50 upper face of said ring, said ports communicating with the space between said casting and valve, locking pawls pivotally mounted in said ports and normally held in engagement with the upper seat, a ring 55 mounted upon said body portion above said conical ring and provided with openings positioned in alinement with the openings leading from said ports, a valve disk slidably mounted upon said body portion for 60 normally closing the openings of said second ring, said flange limiting the upward movement of said valve disk, a hollow piston slidably mounted in said valve, a hollow piston rod passing through said body portion 65 and connected with said piston, means carried by said piston rod for moving said pawls out of engagement with said upper seat, and a valve carried by said piston rod above said upper plug.

6. In a pump of the class described, a casting including plug seats in spaced relation, plugs fitting in said seats, a barrel carried by said plugs, said upper plug being provided with ports communicating with the 75 interior of said barrel and with the space between said valve and casing, a valve carried by the lower plug for controlling the passage of liquid through said casing, a valve carried by said lower plug within said 80 barrel, a valve carried by said upper plug for controlling the passage of liquid through said casing, a hollow piston slidably mounted in said barrel, a hollow piston rod passing through said upper plug and connected 85 with said piston, and a valve carried by said hollow piston rod above said upper plug.

In testimony whereof I hereunto affix my signature in presence of two witnesses.

ARTHUR LEE LIGON.
